(57) CLAIM

The ornamental design for a casing for a laser sight and associated brace, as shown and described.

DESCRIPTION

FIG. 1 is a perspective view of the casing for a laser sight, with the associated brace.

FIG. 2 is a side elevation of the casing for a laser sight, with the associated brace.

FIG. 3 is a top plan view of the casing for a laser sight, with the associated brace.

FIG. 4 is an exploded view of the casing for a laser sight and associated brace.

FIG. 5 is a perspective view of the associated brace.

FIG. 6 is another perspective view of the associated brace.

FIG. 7 is a further perspective view of the associated brace.

FIG. 8 is a left elevation of the associated brace.

FIG. 9 is a right elevation of the associated brace.

FIG. 10 is a front elevation of the associated brace.

FIG. 11 is a rear elevation of the associated brace.

FIG. 12 is a top plan view of the associated brace.

FIG. 13 is a bottom plan view of the associated brace.

FIG. 14 is an alternate perspective view of the casing for a laser sight.

FIG. 15 is another perspective view of the casing for a laser sight.

FIG. 16 is a further perspective view of the casing for a laser sight.

FIG. 17 is a still further perspective view of the casing for a laser sight

FIG. 18 is a left elevation of the casing for a laser sight.

FIG. 19 is a right elevation of the casing for a laser sight.

FIG. 20 is a top plan view of the casing for a laser sight.

FIG. 21 is a bottom plan view of the casing for a laser sight.

FIG. 22 is a front elevation of the casing for a laser sight; and,

FIG. 23 is a rear elevation of the casing for a laser sight.

The broken lines in the figures are for the purpose of illustration portions of the casing for a laser sight and associated brace which are not intended to form a part of the claimed design.
